UNITED STATES PATENT OFFICE.

ANDREW BROWN MACLAREN, OF TORONTO, ONTARIO, CANADA, ASSIGNOR TO E. & A. GUNTHER CO. LTD., OF TORONTO, ONTARIO, CANADA.

RING BOX.

Application filed December 18, 1920. Serial No. 431,792.

To all whom it may concern:

Be it known that I, ANDREW BROWN MACLAREN, a subject of the King of Great Britain, residing in the city of Toronto, 5 county of York, Province of Ontario, Canada, have invented certain new and useful Improvements in Ring Boxes, of which the following is a specification.

My invention relates to improvements in 10 ring boxes, and relates more particularly to the ring-holder, and the object of the invention is to combine the component parts of the ring-holder and form the necessary padding by one operation, and thereby to 15 greatly reduce cost of manufacture of this portion of a ring box and without in any wise impairing the appearance and durability thereof. Another object of the invention is to strengthen the ring box by 20 providing a snug-fitting and substantial ring-holder therefor, and in the following specification I shall disclose my preferred construction and a suitable hand press used in the manufacture of the ring-holder, and 25 what I claim as new will be set forth in the claims forming part of this specification.

Figure 1 is a plan view of the base of 30 the press preferably used in manufacturing the invention, portion of a ring-card and the padding therefor being shown in position. Figure 2 is a vertical longitudinal section on the line 2—2, Fig. 1, showing, in addition, the plunger, partly in section, and suitable guides therefor, which is used with 35 the base; certain additional parts of the ring holder are shown in section in this view. Figure 3 is an elevation of the under side of the plunger. Figure 4 is a vertical 40 central longitudinal section through portion of the base and portion of the plunger, showing these two parts in co-operative relationship in securing the component parts of the ring-holder together. Fig. 5 is a 45 plan view of the ring-card. Figs. 6 and 7 are plan views of the padding and covering respectively for the ring-card. Fig. 8 is a 50 plan view of the ring-holder as it comes from the press, and Fig. 9 is a cross section through a ring-box showing in side elevation the ring-holder mounted therein.

In the drawings like characters of reference refer to the same parts.

It is now commonly the practice to utilize 55 a rectangular-shaped frame in forming a

ring-holder, and then after covering the same to place padding underneath this covering to give the ring-holder the soft domed appearance.

In putting my invention into practice, I 60 stamp the ring-card from a gummed sheet of suitable stock and form therein an opening. I also score this ring-card, thus providing flaps which when broken down form integral sides and ends of the ring-holder 65 to permit the same to be inserted into the box.

I also cut out from the desired material the covering provided with end and side flaps which are designed to be gummed to 70 the flaps of the ring-card before the same are broken down. I also cut out from the desired material the padding and provide a hinge cover of the desired length.

One side of the ring-card is of course 75 coated with any suitable adhesive material, such as glue, and the same is moistened before the ring-card is placed in the base of the press. The padding is then placed in position over the opening in the ring-card, 80 and then over the padding is placed the covering. Where a hinge-cover is used, this hinge-cover is placed on top of the covering. A plunger then descends and a portion of the same passes through the opening formed 85 in said ring-card and into a pocket formed in the base, carrying down with it portion of the padding and covering, as well as portion of the hinge-cover, when used, and in due course the sides of the said plunger 90 press firmly on the flaps of the covering and so bring same intimately in contact with the flaps of the ring-card. Certain portions of the underside of the plunger are recessed so as to prevent the undue crushing of the 95 portions of the padding which are not forced through the opening in the ring-card, thereby providing for the doming or padding of the covering.

During the operation of the plunger, it 100 draws the padding and covering equally from each side of the ring-card so that, by the time binding pressure is applied, the padding and covering shall have been properly positioned, and also the hinge-cover, 105 when used.

A is the ring-card, and the same is stamped from the desired stock, so as to simultaneously cut therein the opening B, and the score lines C. Re-entrant angles D are 110

cut at each corner of the ring-card so that when the flaps E are broken down they will form the ends and sides F and G. These ends and sides of course will be substantially the same height. H is the covering which may be made of any suitable material, and the same is cut to provide end and side flaps I and J. The side-flaps are spaced apart, and they are also spaced apart from 10 the ends of the covering by reason of the re-entrant angles 2.

3 is the padding substantially rectangular in shape, and the same is made of suitable material preferably felt, which is preferably 15 thicker than the material composing the cover H. 4 is the base of the press, and the same is supported in any suitable manner. Formed centrally in the base 4 is a pocket 5. 6 are gauges projecting above the top of 20 the base 4, and positioned substantially equal distances beyond the sides of the pocket 5. 7 are gauges substantially carried by the sides of the base 4, and opposite each other. These gauges of course project above the top 25 of the base 4, and are preferably located so as to project equal distances beyond the sides of the pocket 5. After wetting its gummed surface, the ring-card A is placed upon the base 4 with its sides G against the gauges 6 30 and its ends F against the gauges 7. In this position the opening B is of course in alignment with the pocket 5. 8 are gauges preferably provided with curved ends 9. These gauges project above the top of the base 4 35 and are located adjacent the gauges 6. The padding is placed between said gauges as shown in Fig. 1 so that it may be properly positioned in respect of the ring-card A. 10 are end-gauges formed at each end of the base 4 and projecting thereabove. 11 are side-gauges carried by the base 4 and projecting thereabove. When the covering H 40 is placed over the padding 3, the end-flaps I are placed against the gauges 10 and the side-flaps J are placed against the gauges 11, thereby ensuring that the said covering will 45 be properly positioned and thus overhang at each end the padding 3; 12 is an end-gauge offset from one of the gauges 10, and 50 against this gauge is placed the hinge-cover 13, when used. The position of the parts just described will be clearly understood upon reference to Fig. 2.

14 is any suitable plunger mounted to 55 vertically reciprocate in the uprights 15. The bottom of this plunger is shown clearly on reference to Fig. 3, and it will be seen that the bottom of the said plunger is shaped substantially the same as the ring-card A. 60 16 is a plunger-bar carried by the plunger 14 and depending therebelow and positioned substantially centrally thereof. This plunger is provided preferably with pins 17 which pierce the hinge-cover 13, and the 65 covering H, and the padding 3 as the

plunger 14 descends, and of course the plunger-bar 16, (since it is located directly above the opening B and the pocket 5), as it enters said pocket, will draw the parts just mentioned down into the pocket 5 (see Fig. 70 4) with the result that the ends of the padding 3 will be drawn inwardly over the side flaps E, while at the same time the side-flaps J at each side of the covering H are drawn together over the end flaps E and the end-flaps I of the covering H are drawn towards 75 each other over the side-flaps E. In due course the plunger 14 presses down upon the side-and end-flaps E thus firmly gumming the parts of the covering H in contact with 80 the ring-card A, thereto.

Since each side of the plunger-bar 16 is recessed, as shown at 18, when the plunger 14 is exerting its greatest pressure, while it will press sufficiently upon the parts 19 of the covering H to bring sufficient pressure to bear upon the ends 20 of the padding 3 to unite these ends to the ring-card A, it will be understood that by reason of said recesses 18 undue pressure will not be exerted 90 against the ends 20 to crush the same, because it is these parts of the padding 3 that provide the raised padding or cushions a, as shown clearly in Figs. 8 and 9.

It will be clear upon referring to Fig. 2 95 that the surfaces b of the underside of the plunger 14 will be substantially in the same plane, and are below the plane of the recesses 18, so that pressure may be exerted 100 equally against the side-and end-flaps E.

The end-flaps I are drawn a certain distance within the edges c of the sides G so as to provide sufficient surface on one of the flaps E as shown at d (Fig. 4) so that one 105 end of the hinge-cover 13, if used, can be readily attached to the ring-card A.

The gauge 12 (see Figs. 1 and 2) is offset from one of the gauges 10, and as the hinge cover 13 rests against the gauge 12 it follows 110 that this hinge cover will overhang one end of the covering H and thereby ensure that sufficient of the hinge-cover 13 will overlap the covering H when the parts are in the position shown at Fig. 4.

The surfaces b are not shown in Fig. 4 115 as pressed home for the purpose of clearness in illustration.

Fig. 8 shows a plan view of the ring-holder when lifted from the base 4 after 120 the plunger 14 has been raised, and one end of the ribbon forming the hinge-cover 13 has been pulled out of the ring-socket e (see Fig. 8).

When the plunger-bar 16 is withdrawn, the resiliency of the padding 3 and covering H will cause these parts to assume the position shown in Fig. 8.

The side and end-flaps E are now broken down to form the sides G and ends F of the ring-holder so that the same may be 130

placed in any suitable box F. In Fig. 9 of course the lid of the box is not illustrated.

While I preferably use cloth and felt in making the cover H and padding 3, it will be 5 clear that I may use any other suitable flexible material in place thereof.

While I have disclosed a hand-press for the manufacture of the ring-holder in question, of course it is within the scope of my 10 invention to provide automatic means for this purpose, and I do not confine myself to the constructions herein shown and described except in so far as that may be necessary by reason of the prior art and the terms 15 of my claims.

What I claim as my invention is:

1. As a new article of manufacture, a ring-holder comprising a flat ring-card coated with suitable adhesive material on 20 one side, and provided with a central opening therethrough, and further provided with scored lines located to form side-and end-flaps which are adapted to be broken down; a padding gummed to said card down each 25 side of said opening in such manner as not to overlap said side-and end-flaps, and a covering for said padding adapted to be gummed to said side-and end-flaps and over said padding, and to extend through said 30 opening in the form of a loop.

2. As a new article of manufacture, a ring-holder comprising a flat ring-card coated with suitable adhesive material on one side, and provided with a central opening 35 therethrough, and further provided with scored lines located to form side-and

end-flaps which are adapted to be broken down; a padding gummed to said card down each side of said opening in such manner as not to overlap said side-and end-flaps 40 and adapted to extend through said opening in the form of a loop, and a covering for said padding adapted to be gummed to said side-and end-flaps and over said padding, and to extend through said opening in the form of a loop, which loop will be located 45 within the first-mentioned loop.

3. As a new article of manufacture, a ring-holder comprising a flat ring-card formed from suitable adhesive-coated material and provided with a central opening therethrough and having re-entrant angles formed at each corner thereof and scored on the coated side to form side-and end-flaps 50 designed to be broken down; a padding 55 gummed to said card down each side of said opening in such manner as not to overlap said side-and end-flaps, and adapted to extend through said opening in the form of a loop, and a covering for said padding 60 formed with spaced flaps projecting laterally thereof, and having end-flaps projecting longitudinally beyond the outer sides of said side-flaps; the said covering being 65 gummed to the end-flaps of said ring-card through the medium of its side-flaps, and to the side-flaps of said ring-card through the medium of its end-flaps and covering said padding, and extending through said opening in the form of a loop.

ANDREW BROWN MACLAREN.
